Atty.

UNITED STATES PATENT OFFICE.

JOHN AVERY, OF GALESBURG, ILLINOIS, ASSIGNOR OF ONE-HALF TO
GEORGE W. HUDSON, OF SAME PLACE.

MAIL-BOX.

SPECIFICATION forming part of Letters Patent No. 605,837, dated June 21, 1898.

Application filed June 15, 1897. Serial No. 640,893. (No model.)

To all whom it may concern:

Be it known that I, JOHN AVERY, a citizen of the United States, residing at Galesburg, in the county of Knox and State of Illinois, have invented certain new and useful Improvements in Mail-Boxes, of which the following is a specification.

My invention relates to improvements in mail-boxes.

10 The leading object of the invention is to provide a mail-box with a non-locking lid at its upper end, which lid can be opened to insert mail, which is then received on a hinged swinging plate that forms, when in its closed position, a bottom for the upper or mail-receiving chute and top or closure for a lower mail-delivery compartment or box, and which hinged mail-receiving plate is raised to close access to the lower or delivery compartment 20 or box by the act of raising the non-locking lid to deposit mail in the chute, and thereby upon the hinged mail-receiving plate, and is swung or tilted to its open position by the act of closing said lid, in which open position the 25 tilting plate will deliver the mail contained thereon to the mail-box or delivery-compartment, where it is inaccessible through the hinged-lid opening, as the tilting plate closes access to the lower compartment when the 30 hinged lid is open, and the hinged lid and tilting plate being hinged to opposite sides of the box access cannot be had to the mail below the tilting plate when the hinged lid is partly open.

35 A further object of the invention is to provide a visual signal or indicator which is operatively connected with the hinged lid and the sliding or swinging door through which the mail-matter is removed from the delivery-box in such manner that when said hinged lid is opened for the receipt of mail and closed for the passage thereof to the delivery-compartment when said compartment is empty it exposes the signal to view, but when opened 40 and closed to deliver mail to said compartment while it contains mail the signal will not be affected thereby, said signal not being again operatively connected with the hinged lid until the door through which the mail is 45 taken from the delivery compartment or box is opened.

To the end of carrying out these leading objects of my invention and also further objects thereof and which are hereinafter set forth it consists in certain novel features of construction and arrangement of parts, in novel organization of parts, and in novel combinations of parts, as will be hereinafter fully described, and pointed out in the claims hereto appended.

55 Mechanism embodying the preferred constructive forms of and showing the mutual relationship and combination of parts forming the subject-matter of my improvement is 60 illustrated in the accompanying drawings, in 65 which--

Figure 1 is a side elevation, partly in sectional elevation, of a dual mail-box, in only one of which boxes my improvement is shown; Fig. 2, a side elevation of a single mail-box, 70 partly in sectional elevation, showing the operating parts in different relative positions from those shown at Fig. 1; Fig. 3, a side elevation, partly in sectional elevation, showing the operating parts in different relative positions from those shown at Figs. 1 and 2; Fig. 4, a sectional elevation in the line 4 4 in Fig. 1; Fig. 5, a perspective showing the signal or indicator exposed; Fig. 6, a transverse sectional plan in line 6 6 in Fig. 4.

75 The reference characters herein used indicate, respectively, the same parts in the different figures of the drawings.

At Fig. 1 two similar boxes 1 are shown united, while in the other figures but one box 80 is shown. The boxes may be constructed of wood or metal or any other suitable material and may be fixed in any suitable positions by cleats 2 or otherwise. The box 1 has a lid 3, hinged at 4 to its inclined upper end, preferably in such manner that when closed, as at Figs. 1, 3, 4, and 5, it will remain closed by its own gravity, and when open, as shown at Fig. 2, it will remain open by the same means.

85 About mid-length of the box 1 a plate 5 is 90 hinged at one of its sides to the side of said box which is opposite that side to which the lid 3 is hinged, and a link-rod 6 is pivotally connected at one of its ends with one side of said plate and at its other end with the hinged lid 3 in such manner that closing the lid 3 will 95 swing the plate 5 downwardly to its open po-

sition, as shown at Figs. 1, 3, and 4, and raising or opening the lid 3 will raise the plate 5 to its closed position, as shown at Fig. 2, in which closed position it divides the box 1 into 5 an upper or mail-receiving compartment 7 and a lower or mail-delivery compartment 8. The signal in this instance consists of a colored figure "9," preferably white, painted on the outer surface of the box 1—in this instance within a casing 10, formed of a glass cover 11, held in place by the inturned flanges on the cleats 12. The swinging hood or signal-cover 13 is fixed at one end to a short rocking shaft 14, which is journaled in and 15 extends through the side of the box 1 and has fixed to and projecting from its inner end an arm 15. It will be evident that without departure from the purview of my invention the swinging hood may be colored to represent 20 the plainly-visible signal and that a fixed part, beneath which it is slid, may represent the hood. One end of a chain 16 is secured to the end of the arm 15, and its other end is secured to, in this instance, a sliding 25 door 17, which may, however, be a swinging door or bottom part of the delivery-compartment 8, if preferred. A short pin or lug 18 projects laterally from one side of the link-rod 6 into the path of the swinging arm 15. 30 A spring 19, Fig. 6, on the outer end part of the rock-shaft 14 tends to press the hood 13 into slight frictional contact with the box 1, whereby said hood is held in its horizontal position until moved therefrom, as hereinafter 35 described.

A partition 20, Figs. 4 and 6, separates the link-rod 6, upper end of chain 16, and lug 18 from the mail-receiving compartment 7.

Assuming that both compartments 7 and 8 40 are empty, the working parts will be in the relative positions shown at Fig. 1. Raising the lid 3 for the insertion of mail will therefore raise the plate 5, as shown at Fig. 2, for temporary receipt of such mail, and the lug 45 18, coming in contact with the arm 15, will swing the hood 13 into its horizontal position, and thus expose the visual signal "9." Then closing the lid 3 will swing the plate 5 into its open position, (shown at Figs. 1, 3, 4, and 50 6,) and thereby discharge the mail-matter contained thereon and deliver it to the delivery-compartment 8. In closing the lid 3, as last 55 described, the arm 15 and hood 13 will remain in the positions shown at Fig. 2, as the lug 18 is carried away from the arm 15. In further or again raising the lid 3 for the admission of 60 more mail and closing it again for the delivery thereof to the delivery-compartment 8 the lug 18 will not act on the arm 15, which remains in its position, (shown at Fig. 2,) with the signal "9" exposed to indicate to a mail-carrier or other person the presence of mail 65 in the delivery-compartment 8. Opening the door 17 to the position shown at Fig. 3 for the removal of mail from the delivery-compartment 8 will take up the slack in the chain 16, and drawing down on the arm 15 will swing

the hood 13 into its lower position, thereby covering the signal, to indicate "no mail" in the delivery-compartment. The door 17 being 70 then closed will simply slacken the chain 16 and leave all of the working parts in the relative positions shown at Fig. 1 and ready for operation again, as above described.

It will be observed that when the lid 3 is 75 raised or opened the plate 5, being thereby closed, will cut off access by way of or through the compartment 7 to mail contained in the delivery-compartment 8, and further observed that the act of closing the lid 3 always swings 80 the plate 5 to its open position and delivers all mail contained thereon to the lower compartment 8, and further observed that the lid 3 and plate 5, being hinged to the box at opposite sides thereof, will prevent access to 85 mail below the plate 5 on partly opening the lid 3.

Although I have specifically described the construction and relative arrangement of the several parts of my improved mail-box, yet I 90 do not desire to be confined to the same, as such changes or modifications may be made as fall within the purview of my invention as its subject-matter is set forth in the claims hereto appended.

Having thus described my invention, what I claim as new, and desire to secure by Letters Patent, is—

1. In a mail-box, and in combination, a box, a top therefor hinged to one side of the box, 100 a mail-receiving plate hinged to the side of the box opposite to that to which the top is hinged and extending across and dividing the box when closed into an upper mail-receiving box and a lower mail-delivery box, and a direct link connection connecting said top and plate for moving one by the movement of the other.

2. In a mail-box, and in combination, a box, a hinged lid, a hinged mail-receiving plate 110 dividing the box when closed, into an upper mail-receiving box and a lower mail-delivery box, a link operatively connecting said lid and plate, a signal, a swinging signal-hood, an arm projecting from said hood, and a lug on 115 said link for actuating said hood, substantially as described.

3. In a mail-box, and in combination, a box, a hinged lid, a hinged mail-receiving plate dividing the box when closed, into an upper 120 mail-receiving box and a lower mail-delivery box, a link operatively connecting said lid and plate, a signal, a swinging signal-hood, an arm projecting from said hood, a door to the delivery-box, a chain connecting said door 125 and the arm projecting from the signal-hood, and a lug projecting from said link, substantially as described.

4. In a mail-box, and in combination, a box, a hinged lid therefor, a hinged mail-receiving plate within the box, a link operatively connecting said lid and plate, a swinging signal-hood, means operated by said link-rod for swinging said hood in one direction upon the

opening of the lid, a delivery-door, and a connection between said hood and delivery-door for swinging the hood in the other direction upon the opening of the delivery-door, substantially as described.

5. In a mail-box and in combination, a box, a signal, a receiving-door, movable means operated positively by the receiving-door for disclosing the signal, a delivery-door, and means operatively connecting said delivery-door and means whereby opening the delivery-door will obscure the signal, substantially as described.

6. In a mail-box, and in combination, a box,

a hinged lid, a hinged mail-receiving plate 15 dividing the box when closed, into an upper mail-receiving box and a lower mail-delivery box, a link operatively connecting said lid and hinged plate, a signal, a swinging signal-hood, and a lug on said link operatively connecting said link and signal, substantially as described.

In testimony whereof I affix my signature in presence of two witnesses.

JOHN AVERY.
